APPARATUS FOR LIFTING AND MOVING INVALIDS

Filed June 9, 1928

UNITED STATES PATENT OFFICE

CATHERINE M. COTTMAN, OF ROSEBURG, OREGON

APPARATUS FOR LIFTING AND MOVING INVALIDS

Application filed June 9, 1928. Serial No. 284,166.

My device relates to improvements in apparatus for lifting and moving invalids, and it consists in the combinations, constructions and arrangements hereinafter described and claimed.

An object of my invention is to provide an apparatus for lifting and moving invalids which is designed to have a person-supporting frame normally placed upon a bed or an operating table. This frame has means whereby it may be suspended from a carrier, this carrier having means for raising or lowering the frame, and also means for moving the frame to any place desired.

The device is extremely simple in construction, and may be used for raising any part of the body of the patient above the bed or the operating table when it is desired to work upon the patient or to fix things with respect to him.

Other objects and advantages will appear as the specification proceeds, and the novel features of the device will be particularly pointed out in the appended claim.

My invention is illustrated in the accompanying drawing forming a part of this application, in which:

Figure 1 is a perspective view of the device showing the carrier and the frame suspended therefrom;

Figure 2 is a section along the line 2—2 of Figure 3;

Figure 3 is a top plan view of Figure 2;

Figure 4 shows the fastening means employed for securing the canvas to the frame; and

Figure 5 is a perspective view of a portion of the device.

In carrying out my invention, I provide a canvas sheet 1 that is large enough to cover the bed or the operating table. The patient lies upon this sheet. Eyelets 2 (see Figure 4) are provided adjacent to the marginal edges of the sheet and receive hooks or snaps 3.

The snaps are carried by a steel frame 4 which is rectangular in shape. The frame is large enough to be lowered over the body of the patient, and then the snaps carried by the frame may be secured to the canvas sheet 1. Handles 5 and 6 are hingedly secured to

the ends of the frame 4, and these handles may be manually lifted for moving the patient from place to place, or they may be raised and supported by a mechanism now to be described.

Each handle carries eyelets 7 at the two upper corners thereof. To these eyelets I secure steel cables 8 or other suitable supporting means. Reference to Figures 2 and 3 shows how the cables 8 are passed over idlers 9 carried by transverse bars 10 that in turn are slidably mounted in grooved rails 11.

The rails are cylindrical and have slots cut in their upper edges and in their tops. These slots receive lugs 12 carried by the transverse bars 10, and the lugs have enlarged heads which prevent vertical movement of the bars but permit sliding movement along the rails. The rails permit the bars to be removed entirely if desired.

At the center of each bar 10 I mount a hand wheel 13 that has an internally threaded hub 14 adapted to receive a screw 15, the latter being rigidly secured to the transverse bar 10. The cables 8 are secured to the hub 16 as shown in Figure 3. Guide pulleys 17 are disposed adjacent to the hub and align the cables 8 with the idlers 9. A turning of the hand wheels 13 will raise the frame 4, which in turn will lift the patient.

The rails 11 form a part of a carrier indicated generally at 18. This carrier has legs 19 mounted upon casters 20, and one set of legs is disposed far enough from the other set to permit the carrier to straddle a bed or an operating table.

From the foregoing description of the various parts of the device, the operation thereof may be readily understood.

The patient is assumed to be already lying upon the canvas sheet 1. The frame 4 is now secured to the sheet and then the frame is raised by means of the hand wheels 13 and is supported by the carrier 18. The carrier may now be moved to the new location, and then the frame 4 again lowered in order to dispose the sheet 1 on the bed or the operating table, as the case may be. The snaps 3 are

unfastened and the frame and the carrier may be moved away.

Sometimes it is necessary to raise only a part of the patient's body. In this instance, 5 I provide a canvas strip 21 having eyelets 22 securable to the snaps 3. The snaps are placed at different positions along the frame 4, and therefore the strip can be secured at different places for raising any part of the 10 patient's body desired.

Although I have shown and described one embodiment of my invention, it is to be understood that the same is susceptible of various changes, and I reserve the right to employ 15 such changes as may come within the scope of the appended claim.

I claim:

A device for moving invalids comprising a carrier having longitudinally-extending 20 rails, each being cylindrical in cross section and having a slot in its top extending throughout the entire length; frame-carrying bars extending at right angles to the rails and having lugs with enlarged heads slidably received in the rails, whereby said bars can only slide longitudinally in the rails; a patient-supporting frame; hand wheels carried by said bars; and cables wound about said wheels and passed over said bars, the ends of said 30 cables being secured to said frame.

CATHERINE M. COTTMAN.
